DESIGN FOR A SPANISH DOLL SOUVENIR TEA BELL

Charlotte E. Hollander, Baton Rouge, La.

Application February 27, 1945, Serial No. 118,163

Term of patent 14 years

(Cl. D10—4)

To all whom it may concern:

Be it known that Charlotte E. Hollander, a citizen of the United States of America, residing at Baton Rouge, in the parish of East Baton Rouge and State of Louisiana, has invented a new, original, and ornamental Design for Spanish Doll Souvenir Tea Bell, of which the following is a specification, reference being had to the accompanying drawing, forming part thereof.

I claim:

The ornamental design for a Spanish doll souvenir tea bell, as shown.

CHARLOTTE E. HOLLANDER.
